UNITED STATES PATENT OFFICE.

WILLIAM E. HALE, OF FORT WASHINGTON, PENNSYLVANIA, ASSIGNOR TO R. H. BEAUMONT COMPANY, OF PHILADELPHIA, PENNSYLVANIA, A CORPORATION OF PENNSYLVANIA.

DRAG-SCRAPER EQUIPMENT.

Application filed January 9, 1924. Serial No. 685,141.

To all whom it may concern:

Be it known that I, WILLIAM E. HALE, a citizen of the United States, residing at Fort Washington, in the county of Montgomery and State of Pennsylvania, have invented a new and useful Improvement in Drag-Scraper Equipments, of which the following is a specification.

Objects of the present invention are, first, 10 to provide drag scraper equipment in which a single powerhouse and scraper can be employed for handling material over two adjacent yard storage areas and from two spaced dumping points interposed in a railway line; and second, to accomplish the 15 above object by the use of comparatively short girder structures at the dumping points.

To these and other ends the invention, 20 generally stated, may be said to comprise an elevated railway line, spaced dumping spans interposed in the line, a yard situated in front of the line and comprising two contiguous storage areas with space between them, a powerhouse located in said space, 25 front and back guide pulleys operatively arranged in respect to the powerhouse and respectively located back and front of the line, a front block structure for both storage areas and each said structure co-operating 30 with the front guide pulley, and a back block structure under and at the back and front and ends of each dumping span and each said structure co-operating with the 35 back guide pulley.

Other objects of the invention as well as the nature and characteristic features thereof will appear from the following description which will be made in connection with 40 the embodiment of the invention chosen for the sake of illustration in the accompanying drawings forming part hereof and in which—

Figure 1 is a diagrammatic plan view 45 illustrating drag scraper equipment embodying the invention, and

Fig. 2 is an end view of one of the dumping spans.

In the accompanying drawings 1 is an 50 elevated railway line shown as straight, although it may be curved. 2 and 3 are spaced dumping spans interposed in the line. Each dumping span usually consists of a girder structure 4 carrying rails and supported at its ends by trestles or abut-

ments 5. It is an advantage of the invention that the girder structures may be comparatively short while at the same time the storage areas are bounded by comparatively wide angles as will appear from the following description. There is a yard situated in front of the line and comprising two storage areas with space between them. The powerhouse 6 is located in that space and a single scraper 7 cooperates with both of the dumping spans and with both of the storage areas. The front and back guide pulleys 8 and 9 are operatively arranged in respect to the powerhouse 6 and are respectively located at the front and 60 back of the line. A front block structure 10 is provided for both storage areas and each said structure co-operates with the front guide pulley 8. The back block structure 11 is provided at each dumping span and each said structure co-operates with the back guide block 9 and is disposed under and at the ends and back and front of the spans. The storage yard is bounded by the front block structure 10, and the powerhouse 65 space is bounded by a railway line and by boundaries *a* and *b*, which with the line *c* and *d*, include the angles *e*, which define and limit the area over which the scraper 7 may work to handle material beneath the 70 dumping span. The lines *a* and *b* bound the space where the powerhouse is located and in respect to the storage areas and the latter are limited or bounded by the lines *c* and *d*.

The operation of the drag scraper equipment may be described as follows:

The material, generally indicated at 12 and dumped from a car 13, may be distributed over each storage area, and this is done 95 by appropriately shifting the cables which operate the drag scraper 7 in respect to the front and back blocks which, as shown, comprise a series of blocks but which may consist of blocks that are moved. In the 100 drawings the full and dotted lines indicate arrangements of the cables for causing the scraper to work over certain parts of the storage area and in each case the front and back guide pulleys are employed as 105 shown. The angle *e* between the full and dotted lines at the left in the drawings shows that the space over which the drag scraper may work is bounded by a wide or obtuse angle.

It will be obvious to those skilled in the art to which the invention relates that modifications may be made in details of construction and arrangement and in matters 5 of mere form without departing from the spirit of the invention which is not limited as to such matters or otherwise than as the prior art and the appended claim may require.

10 I claim:

Drag scraper equipment comprising an elevated railway line, spaced dumping spans interposed in the line, a yard situated in front of the line and comprising two con-

tiguous storage areas with space between 15 them and the line, a powerhouse located in said space, front and back guide pulleys operatively arranged in respect to the powerhouse and respectively located front and back of the line, a front block structure 20 bounding the yard and common to each storage area and said structure co-operating with the front guide pulley, and a back block structure disposed at the back and front and ends and under each dumping 25 span and each said back block structure co-operating with the back guide pulley.

WILLIAM E. HALE.
